UNITED STATES PATENT OFFICE.

WILLIAM T. DUNNING, OF RIDLEY PARK, PENNSYLVANIA.

AIR-HEATING DEVICE FOR STOVES.

1,190,873.

Specification of Letters Patent. Patented July 11, 1916.

Application filed March 9, 1915. Serial No. 13,249.

To all whom it may concern:

Be it known that I, WILLIAM T. DUNNING, a citizen of the United States, residing at Ridley Park, in the county of Delaware and State of Pennsylvania, have invented a certain new and useful Improvement in Air-Heating Devices for Stoves, whereof the following is a specification, reference being had to the accompanying drawing.

10 My improvement relates to devices including a stove lid having a tortuous air passageway leading from the top thereof to the interior of the stove; said lid having at the top thereof a valve controlling the effective area of the inlet to said passageway.

In the form of my invention hereinafter described the tortuous passageway is a slightly conical helical spiral, formed entirely in a single casting which is primarily 20 separate from the lid but removably attached thereto, with a disk gasket formed of a sheet of flexible material which is a non-conductor of heat between said casting and lid, and the inlet is at the outer end of the 25 spiral but communicates directly with the center of the spiral by a radial passageway; so that the air passes downwardly through the lid at the outer convolution of the spiral, thence radially inward to the center convolution of the spiral and thence spirally outward and downward from the center of the 30 spiral to radially opening outlets in the outer convolution thereof through which the air is discharged beneath the lid to the interior of the stove.

My invention includes the various novel features of construction and arrangement hereinafter more definitely specified.

In the drawings; Figure I is a plan view 40 of a stove lid embodying my improvement. Fig. II is an inverted plan view of said lid. Fig. III is a sectional view of said lid, taken on the line III, III in Figs. I and II and showing its relation to the stove lid.

45 In said figures; the stove top 1 has the lid opening 2 with the flange 3, to receive and support the lid 4. Said lid 4 is a single plane casting having an air inlet 6 opening therethrough, controlled by the slide valve plate 7 which is fitted to reciprocate in the 50 depression 9 in the top of the lid in which it is held by the rivet 10 which extends through the slot 11 in said plate. Said plate 7 has the groove 12 in its upper surface by which it may be engaged to be slid, 55 and has the index 14 to selectively register

with the graduations 15 in the respective positions of said valve indicated by the words "Off" "Night" "Hot" which are conveniently formed by raised letters in the depression 16 in the top of the lid. When in the position indicated by the word "Off" said valve entirely closes the air inlet. When in the position indicated by the word "Night", said valve partly closes said inlet, 60 and when in the position indicated by "Hot" said valve leaves the inlet fully opened. Said inlet opens into a tortuous passageway 18 which is formed entirely in the single casting 19 which is primarily separate from 70 said lid 2 but is removably attached thereto conveniently by the three screws 20 in the disk gasket 21, formed of a sheet of flexible asbestos fabric or other material which is a non-conductor of heat, between said casting 75 and lid. Said inlet 6 is at the outer end of the spiral passageway 18 in said casting, but communicates directly with the center of said spiral by the radial passageway 24; so that the air passes downward through the 80 lid at the outer convolution of the spiral, thence radially inward to the center convolution of the spiral and thence spirally outward and downward from the center of the spiral to the radially opening outlets 25 in 85 the outer convolution thereof through which the air is discharged beneath the lid to the interior of the stove. It may be observed that said casting 19 is conically hollow and spirally corrugated upon its under surface 90 to concentrate, upon said casting, the heat from the fire beneath it, and to present for absorption of such heat a larger surface than would be presented if said casting were plane faced. Moreover, the tortuous passageway 18 is formed in said casting by the 95 spiral rib 26 in unitary relation with said casting and affording a maximum surface thereof for exposure to the incoming air, to impart to it the heat absorbed as aforesaid. 100 It is to be understood that the atmospheric air is caused to flow inwardly from the outer atmosphere to the interior of the stove through the tortuous passageway in the heating device above described, by the ordinary draft of the stove; although the influx of air through said passageway is controllable by the slide valve above described, independently of the means controlling such 105 ordinary draft.

110 I do not desire to limit myself to the precise details of construction and arrangement

herein set forth as it is obvious that various modifications may be made therein without departing from the essential features of my invention as defined in the appended claims.

5 I claim:—

1. The combination with a stove lid having a rectangular air inlet leading from the top thereof to the interior of the stove, a plane depression including said inlet and 10 extending therefrom toward the center of the lid, another plane depression adjoining the first named depression, a series of graduations upon the portion of the lid between said depressions, and means forming the 15 words "Off", "Night" and "Hot" in the last named depression respectively corresponding with marks in said series of graduations; of a plane rectangular slide valve plate fitted to reciprocate in the first named 20 depression, to vary the effective area of said inlet, and having a slot therein, extending radially with respect to the lid; a rivet, extending through said lid and said slot in said plate and having a head in the latter 25 preventing the removal of said plate; a single casting primarily separate from said lid, having a conical spiral air passageway formed therein, by an upwardly extending spiral rib in unitary relation with said casting, with the outer end of said passageway 30 registering with said inlet in said lid, and having a radial passageway leading directly from said outer end of the spiral to the center thereof, and radially opening outlets at 35 the outer convolution of said spiral, opening to the interior of the stove; a disk gasket, formed of a sheet of material which is a nonconductor of heat, interposed between the under side of said lid and the top of said 40 casting; means removably connecting said lid, casting and gasket in assembled relation, including three screws symmetrically disposed with respect to said lid, extending through the latter in engagement with said 45 casting; whereby a stream of air may be heated and discharged through said lid into the stove at a rate and temperature affected by said valve.
2. The combination with a stove lid having an air inlet leading from the top thereof to the interior of the stove, a depression including said inlet, another depression adjoining the first named depression, a series 50 of graduations upon the portion of the lid between said depressions, and means forming the words "Off", "Night" and "Hot" in the last named depression respectively corresponding with marks in said series of 55 graduations; of a plane slide valve plate fitted to reciprocate in the first named depression, to vary the effective area of said inlet, and having a slot therein, extending radially with respect to the lid; a rivet, extending through said lid and said slot in 60 said plate and having a head in the latter 65

70 preventing the removal of said plate; a single casting primarily separate from said lid, having a conical spiral air passageway formed therein, by an upwardly extending spiral rib in unitary relation with said casting, with the outer end of said passageway 75 registering with said inlet in said lid, and having a passageway leading from said outer end of the spiral to the center thereof, and outlets at the outer convolution of said spiral, opening to the interior of the stove; a disk gasket, interposed between the under 80 side of said lid and the top of said casting; means removably connecting said lid, casting and gasket in assembled relation, including screws extending through the lid in engagement with said casting; whereby a stream of air may be heated and discharged through said lid into the stove at a rate and 85 temperature affected by said valve.

3. The combination with a stove lid having an air inlet leading from the top thereof to the interior of the stove, a depression including said inlet, a series of graduations upon the lid, and means forming the words 90 "Off", "Night" and "Hot" respectively corresponding with marks in said series of graduations; of a valve fitted in the first named depression, to vary the effective area of said inlet, and having a slot therein, extending radially with respect to the lid; a rivet, extending through said lid and said slot in said plate and having a head in the latter 95 preventing the removal of said plate; a single casting primarily separate from said lid, having a conical spiral air passageway formed therein, by an upwardly extending spiral rib in unitary relation with said casting, with the outer end of said passageway 100 registering with said inlet in said lid, and having a passageway leading from said outer end of the spiral to the center thereof, and outlets at the outer convolution of said spiral, opening to the interior of the stove; a disk gasket, interposed between the under side 105 of said lid and the top of said casting; means connecting said lid, casting and gasket in assembled relation, extending through the lid in engagement with said casting; whereby a stream of air may be heated and 110 discharged through said lid into the stove at a rate and temperature affected by said valve.

4. The combination with a stove lid having an air inlet leading from the top thereof to the interior of the stove, a depression including said inlet, a series of graduations upon the lid, and means forming the words 115 "Off", "Night" and "Hot" respectively corresponding with marks in said series of 120 graduations; of a valve fitted in the first named depression, to vary the effective area of said inlet, and having a slot therein, extending radially with respect to the lid; a rivet, extending through said lid and said 125 casting, with the outer end of said passageway registering with said inlet in said lid, and having a passageway leading from said outer end of the spiral to the center thereof, and outlets at the outer convolution of said spiral, opening to the interior of the stove; a disk gasket, interposed between the under side of said lid and the top of said casting; means connecting said lid, casting and gasket in assembled relation, extending through the lid in engagement with said casting; whereby a stream of air may be heated and 130 discharged through said lid into the stove at a rate and temperature affected by said valve.

slot in said plate and having a head in the latter preventing the removal of said plate; a single casting primarily separate from said lid, having a spiral air passageway formed therein, by an upwardly extending spiral rib in unitary relation with said casting, with the outer end of said passageway registering with said inlet in said lid, and having a passageway leading from said outer end of the spiral to the center thereof, and outlets opening to the interior of the stove; a gasket, interposed between the under side of said lid and the top of said casting; means connecting said lid, casting and gasket in assembled relation, extending through the lid in engagement with said casting; whereby a stream of air may be heated and discharged through said lid into the stove at a rate and temperature affected by said valve.

5. The combination with a stove lid having an air inlet leading from the top thereof to the interior of the stove, of a valve fitted to vary the effective area of said inlet, and having a slot extending radially with respect to the lid; a rivet, extending through said lid and said slot in said plate and having a head in the latter preventing the removal of said plate; a single casting primarily separate from said lid, having a spiral air passageway formed therein, by an upwardly extending spiral rib in unitary relation with said casting, with the outer end of said passageway registering with said inlet in said lid, and having a passageway leading from said outer end of the spiral to the center thereof, and outlets opening to the interior of the stove; a gasket, interposed between the under side of said lid and the top of said casting; and means connecting said lid, casting and gasket in assembled relation.

6. The combination with a stove lid having an air inlet leading from the top thereof to the interior of the stove, of a valve fitted to vary the effective area of said inlet, and having a slot extending radially with respect to the lid; a rivet, extending in said slot and preventing the removal of said plate; a single casting primarily separate from said lid, having a spiral air passageway formed therein, by an upwardly extending spiral rib in unitary relation with said casting, with the outer end of said passageway registering with said inlet in said lid, and having a passageway leading from said outer end of the spiral to the center thereof, and outlets opening to the interior of the stove; a gasket, interposed between the under side of said lid and the top of said casting; and means connecting said lid, casting and gasket in assembled relation.

7. The combination with a stove lid having an air inlet leading from the top thereof to the interior of the stove, of a valve fitted to vary the effective area of said inlet, and having a slot; a rivet, extending in said slot and preventing the removal of said plate; a single casting primarily separate from said lid, having a spiral air passageway formed therein, by an upwardly extending spiral rib in unitary relation with said casting, with the outer end of said passageway registering with said inlet in said lid, and having a passageway leading from said outer end of the spiral to the center thereof, and outlets opening to the interior of the stove; a gasket, interposed between the under side of said lid and the top of said casting; and means connecting said lid, casting and gasket in assembled relation.

8. The combination with a stove lid having an air inlet leading from the top thereof to the interior of the stove; of a single casting primarily separate from said lid, having a spiral air passageway formed therein, by an upwardly extending spiral rib in unitary relation with said casting, with the outer end of said passageway registering with said inlet in said lid, and having a passageway leading from said outer end of the spiral to the center thereof, and outlets opening to the interior of the stove; a gasket, interposed between the under side of said lid and the top of said casting; and means connecting said lid, casting and gasket in assembled relation.

9. The combination with a stove lid having an air inlet leading from the top thereof to the interior of the stove; of a single casting primarily separate from said lid, having a spiral air passageway formed therein, by an upwardly extending spiral rib in unitary relation with said casting, with the outer end of said passageway registering with said inlet in said lid, and having a passageway leading from said outer end of the spiral to the center thereof, and an outlet opening to the interior of the stove; a gasket, of refractory material, interposed between the under side of said lid and the top of said casting; and removable means detachably connecting said lid, casting and gasket in assembled relation.

10. The combination with a stove lid having an air inlet leading from the top thereof to the interior of the stove; of a single casting having a spiral air passageway formed therein, by an upwardly extending spiral rib in unitary relation with said casting, with the outer end of said passageway registering with said inlet in said lid, and having a passageway leading from said outer end of the spiral to the center thereof, and an outlet opening to the interior of the stove.

stove; and removable means detachably connecting said lid and casting.

11. The combination with a stove lid having an air inlet leading from the top thereof to the interior of the stove; of a single casting having a spiral air passageway formed therein, by an upwardly extending spiral rib in unitary relation with said casting, with the outer end of said passageway registering with said inlet in said lid, and having a passageway leading from said outer end of the spiral to the center thereof, and an outlet opening to the interior of the stove; and means rigidly connecting said lid and casting.

12. The combination with a stove lid having an air inlet leading from the top there-

of to the interior of the stove; of a single casting having a spiral passageway formed therein with an outlet opening to the interior of the stove, at the outer end of said passageway, and having a radial passageway extending from the inner end of said spiral passageway to said air inlet said radial passageway crossing the outer convolutions of said spiral passageway without communication therewith.

In testimony whereof, I have hereunto signed my name at Philadelphia, Pennsylvania, this sixteenth day of February, 1915.

WILLIAM T. DUNNING.
